APPARATUS FOR PUMPING WELLS

Irving C. Harris, Milwaukee, Wis., and Harry W.
Doubrava, Beverly Hills, Calif.

Application March 25, 1932, Serial No. 603,114

9 Claims. (Cl. 103—231)

This invention relates to pumping methods used in pumping fluids from deep holes in the earth, as from wells drilled for petroleum.

The deep lying formations from which petroleum is obtained, contain gas mixed with the oil and under high pressure. When the wells are first completed, the gas pressure usually brings the oil to the surface of the ground; and the wells flow oil and gas for a period of time, after which, the gas pressure is not sufficient to bring the oil to the surface; and then it is necessary to use other methods to lift the oil to the surface of the ground. Quite satisfactory results have been obtained with the various methods heretofore used as long as the lift from the level to which the gas brings the oil to the surface of the ground is not excessive.

Of late years, wells by the hundreds have been drilled to depths of from 4000 to 8000 feet; and such wells produce oil for a limited time without pumping. For a considerable time after the gas pressure has ceased to be sufficient to bring the oil to the surface of the ground, it still brings the oil a large part of the way; and various methods are used with success in bringing the oil to the surface by assisting the gas pressure. As the gas pressure declines, the difficulties of lifting oil by means of the "sucker-rod" pumps and various other methods used, increase until a point is reached where abandonment follows due to the inability of pumping from 4000 to 8000 foot depths without the assistance of the virgin gas pressure in the wells.

Most of the deep wells are quite crooked and the casings small; and the mechanical troubles and maintenance expense with "sucker-rod" pumps are very severe. Many air and gas lift systems have objectionable features and hazards due to their producing surges or severe and sudden changes in pressure between the inside and the outside of the well casing, and due to the application of excessive pressure tending to drive the oil back into the oil-bearing formations.

It is an object of our invention to provide a means of lifting oil from the bottom of wells of any depth without dependence upon the lifting effect of the gas within the oil-bearing structure, without the application of back-pressure to the oil structure while pumping, and without submitting the wells and their casings to severe, sudden and harmful changes in pressure.

It is an object of our invention to provide a means of pumping from the bottom of a well after the virgin pressure has been depleted to a point where the gas pressure will not lift the oil above

the top of the oil-bearing formation and the oil enters the well by gravity seepage and slight residual gas pressure, or as the result of repressuring operations.

Another object is to provide a system of pumping in which the apparatus installed within the well is of maximum simplicity and reliability and such as to produce a minimum of wear and hazard of damage to the casing of the well and the formation surrounding it. 5

Another object is to provide a system of pumping in which oil and gas are used under conditions permitting high economy and a minimum of wastage of oil and gas. 10

We attain the objects of this invention by the means illustrated in the accompanying drawing, in which, Fig. 1 is a section through the axis of the portion of the mechanism installed in the well, and a schematic diagram of the apparatus connected to and operable with that installed 20 in the well, and Fig. 2 is a view of a nozzle sleeve.

The string of pipe or tubing 1, in Fig. 1, is the outer tubing, which is installed in the well and supported at the casing head. A machined shoulder is provided at the lower end, as indicated at 25 4, and machined seats against which the packings indicated at 5, 6, and 7 bear, for receiving the mechanism installed within the tubing 1. The shoulder 4 prevents the mechanism from passing beyond the end of the tubing 1. 30

A string of pipe, or tubing, designated the intermediate tubing 3, is installed within the outer tubing and supported by supporting means at the casing head. Attached at the lower end of the intermediate tubing is an assembly of parts, 35 the enclosing housing of which is indicated at 10. The packings indicated at 5, 6, and 7 make fluid-tight contact with the outer tubing.

Installed within the intermediate tubing 3 is an assembly of tubing and rod sections, indicated 40 at 2, forming the inner tubing, or gas-discharge-line. The said assembly is suspended at the derrick by a mechanism including rod 18, packing 17, lever 19, walking-beam 5, and counterweight 20 in such a way that the inner tubing may be reciprocated vertically through a short distance by actuating cylinder 21, which is controlled by timing and control mechanism 22. Cylinder 22 may be actuated by oil pressure from the oil pump 23; and this oil may be exhausted into the oil-tank 50 and gas-trap 25. The inner tubing connects with the housing 10 by means of telescopic joint including packings 70. 45

Connected into the string of inner tube sections 2, or the gas-discharge-line, are valves of a check- 55

valve type permitting flow of fluid from the gas-discharge-line into the space between the gas-discharge-line 2 and the intermediate tubing 3, when the relative pressures permit, but not in the 5 reverse direction. Two of these valves are indicated at 68 in Fig. 1. One or more of these valves may be used. When two or more are used, they are placed at intervals at different elevations between the mechanism in the housing 10 and the 10 ground level.

A gas compressor, or its equivalent in the way of a connection to a pipeline system connecting with a central compressor plant, is indicated at 65; and 23 represents an oil-pump, 24 a second 15 compressor, or equivalent, 25 a gas-trap including an oil-tank with a small oil storage capacity, and 28 is a mixer.

In operation, oil-pump 23 draws oil from the 20 gas-trap and oil-tank 25 and delivers it at the required pressure at the mixer 28; and the gas compressor 24 takes gas from the gas-trap and from compressor 65 and compresses it to the required pressure and delivers it to the mixer 28. The flows of the fluids are shown by arrows. 25 The oil and gas are mixed in proper proportion at mixer 28; and the mixture is forced down the space between the outer tubing 1 and the intermediate tubing 3, as indicated by the arrows, and through the passageways in the housing 10 and 30 into the separator chamber 33 through nozzles 32.

A portion of the gas is separated from the oil in separator chamber 33 and used through displacement chamber 40, as hereinafter described; and the gas not thus separated and used, and 35 all of the oil, plus the virgin oil pumped and injected into the stream at 35, as hereinafter described, passes upward through the passageway in housing 10, indicated at 35, 36, and 71, and in the space between the intermediate and inner 40 tubings, as indicated by the arrows, and out at outlet 30, whence the mixture of gas and oil goes to the gas-trap and oil-tank 25, where the gas and oil are separated, a part of the oil going to the oil-pump 23 again, and the gas going to the 45 compressor 24 again, thus completing the circuit. The gas separated out at the separator 33 and used through the displacement chamber, as herein described, passes upward between the outer casing 1 and the well casing and out at outlet 29, where 50 it is led to compressor 65 and compressed and delivered to the connection between the gas-trap and compressor 24 at the pressure maintained at that point, thus completing the circuit for that part of the original quantity of gas. The increase 55 of oil due to the virgin oil pumped and injected at 36, as described, is taken out of the circuit at outlet 44; and any excess of gas due to virgin gas coming in with virgin oil, or any deficiency of gas due to losses, is equalized by withdrawal from or 60 injection into the circuit at 27 by means not shown. The oil-pump and compressors are adjusted to operate at the pressure and rates of delivery of fluid required to maintain the circulation described.

65 The descending and ascending columns of fluid balance each other except for the difference in weight due to the different amounts of gas contained in the two. The pressures supplied by the oil-pump and compressors are required to be high 70 enough to overcome the stated difference in weight and to do the work required to overcome the friction and slippage losses and maintain the circulations. These pressures are small compared with the pressures existing at the bottom of the 75 circuit. The gas enters the circuit at mixer 28

at a certain pressure and is compressed as it descends to the bottom with the oil until, at the bottom of the circuit, it has a pressure several times the pressure at which it enters the circuit. The pressure in chamber 33 is that due to the 5 weight of the column of liquid and gas in the descending column between the tubings 1 and 3, plus the initial pressure at 28, minus friction losses. It is, also, equal to that due to the weight of liquid and gas in the ascending column within 10 tubing 3, plus and back pressure at 25, plus friction losses. The apparatus thus operated acts as a high-pressure, hydro-pneumatic compressor, delivering high-pressure gas at the bottom of the 15 circuit.

The mixture of oil and gas passes from the inner tubing into the mechanism at the bottom through nozzles 32, by means of which, the mixture is directed in a spiral direction down the outer cylindrical wall of the separator chamber 20 33, causing a whirling or vortex movement within the chamber which separates the gas and oil, the oil going to the outside and the gas to the center on account of the large difference in the specific 25 gravities of the two fluids. A portion of the separated gas goes toward the center and to the top of the separator chamber and is taken out at outlet 34, as hereinafter described. The remainder of the gas and all of the oil passes out of the chamber at outlet 35 through a duct between 35 and 36, which is made of small cross-sectional 30 area so as to produce a desired drop in pressure between 35 and 36, and flows upward from the end of the duct at 36 in the passageway 71 and to the surface of the ground in the space between the inner and intermediate tubings, and thence 35 into the gas-trap 25.

In the lower part of the mechanism at the bottom of the well is a displacement chamber 40, which is operated in somewhat the same manner 40 as the usual displacement chamber, air-lift pump. Parts 41 and 42 are valves controlling oil and 46, 47, 60, and 69 are valves controlling gas. The valves 46, 47, and 60 are operated in proper sequence and timing by the reciprocating movement of the inner tubing 2, as previously described, through the medium of cams 48, 49, and 61, springs 58, 59, and 66, and bell-cranks 50, 51, and 62, respectively. Valve 69 is a check-valve to prevent reverse flow through valve 60.

Valves 46, 47, and 60 are held in the closed position against the valve seats by the springs 58, 59, and 66, respectively, and are opened when the bell-cranks 50, 51, and 62, engaging the respective valve stems, are actuated by riding up on the cams 28, 49, and 61, respectively, in sequence. Valve 46 is shown in the open position and valves 47 and 60 in the closed position in the drawing.

When the inner tubing 2, with the attached cams is moved axially an amount sufficient to cause bell crank 50 to ride down cam 48 under the pressure of spring 58, valve 46 is closed. When the axial movement has progressed enough to cause bell crank 62 to ride up on cam 61, valve 60 is opened, valves 46 and 47 remaining closed. 65 This is the second position in a sequence, the position in which valve 46 is open and valves 60 and 47 closed being the first. A further movement of the inner tubing 2 with the attached cams causes valve 47 to be opened by bell crank 51 riding up on cam 49, valves 46 and 60 still remaining open. This is the third position in the sequence. Travel of the inner tubing 2 with the attached cams in a reverse direction to the position of starting, as described above, with valve 46 open and valves 60 70 75

and 47 closed, completes the cycle. The three valves 46, 60 and 47 may be operated in the desired sequence and with pauses of the desired length in the three positions described by proper proportioning of the cams and the mechanism for reciprocating the inner tubing. The mechanism for reciprocating the inner tubing is no part of the present invention and is not detailed.

When the inner tubing and the attached cams are in a position such that valve 46 is open and valves 47 and 60 are closed, the displacement chamber 40 is connected to the separator chamber 33 through passageway 34 and isolated from the well. When thus connected and when the circulation of the mixture of gas and oil is operative, the pressure in the separator chamber 33, due to the difference in weight between gas in passageway 34 and oil and gas in the passageway between 35 and 36 and between the levels of the liquid in the two chambers, and, also, due to the drop in pressure between 35 and 36 caused by the small size of the passageway, as previously described, is higher than the pressure in the displacement chamber. The pressure in the displacement chamber 40 when valve 42 is open and liquid is being forced out of the chamber through valve 42 and tubing 3 to the gas-trap 25, is fixed by the pressure maintained in the gas-trap 25 and the conditions of flow and pressure in the column of fluid between chamber 40 and gas-trap 25. The pressure exerted by pump 23 and compressor 24 is made high enough to force a circulation of fluid through separator chamber 33, as described; and the pressure in chamber 33 is made higher than the pressure in chamber 40 by purposely making a friction drop of a desired amount in the passageway between 35 and 36. The pressure in chamber 33 being higher than the pressure in chamber 40, the gas must flow from chamber 33 into chamber 40 and displace the liquid in chamber 40.

The relationships of pressure and the resulting flows may be more readily observed from a study of the diagrammatic representation of the apparatus shown in Fig. 2, in which the relationships of pressure are indicated by the relative position of the different parts in the figure. Pump 23 and compressor 24 receive fluid from the gas-trap 25 and create and maintain the pressure at 28 at the necessary value to force the circulation. Compressor 65 receives gas from the well at low pressure and delivers it at the pressure maintained in gas-trap 25. With these relationships properly adjusted, the circulations of fluid indicated by the arrows and described herein must follow in accordance with the natural laws governing the flow of liquids and gases. The effect and purpose of this is to cause gas, separated from the oil in the separator chamber, as described, to flow through the passageway 34 and valve 46 into the displacement chamber 40 and displace any oil in the chamber and cause it to open the check-valve 42 and pass out into the stream of gas and oil ascending from the separator in the passageway at 36.

When the displacement chamber 40 is filled with gas and the inner tubing and its attached cams are moved axially with reference to the housing 10 and sliding through packings 10, to such a position as to close valve 46 and open valve 60, valve 47 remaining closed, the gas in displacement chamber 40 will flow into the inner tubing, or gas-discharge-line, through valve 60, and raise the pressure in that line to values higher than the pressures in the space between the inner and intermediate tubings and open the valves 68,

which are placed at intervals in the lower one-half to three-quarters, or more, of the length of the gas-discharge-line, and allow gas to flow from the gas-discharge-line into the outer space as long as the pressure remains higher in the gas-discharge-line. As the pressure falls, the valves 68 will close in succession, beginning with the lower one; and the pressure in the displacement chamber and the gas-discharge-line will fall until it equals the pressure in the space between the inner and intermediate tubings at the elevation of the uppermost valve 68. The valves 68 will prevent any reverse flow.

When the pressure in the displacement chamber has been reduced as described and the inner tubing and its attached cams are moved so as to open valve 47, valve 60 remaining open and valve 69 automatically closing to prevent reverse flow through it and valve 60, valve 46 remaining closed, the gas remaining in displacement chamber 40 discharges through valve 47 and outlet 54 into the well in the space between the outer tubing and the well casing; and oil from the well opens the foot-valve 41 and passes into the displacement chamber 40 through inlet 67, valve 41, and passageway 43.

When the displacement chamber is full of oil and the inner tubing and its attached cams are moved to a position so as to close valves 47 and 60 and open valve 46, gas from the separator chamber 33 flows into the displacement chamber and displaces and forces the new charge of virgin oil into the circulation of oil and gas as previously described, thus completing the cycle of operation of the displacement chamber.

From the foregoing description, it will appear that the virgin oil is injected into the circulating flow of oil and gas mixture maintained by the oil-pump and compressors, as previously described, by a displacement, or air-lock, method in which the gas at the pressure existing at the bottom of the circuit is exchanged for an approximately equal volume of virgin oil. After being injected into the circuit at the bottom, the virgin oil is brought to the surface of the ground by the circulation of the mixture. When the exchange of gas for oil is being made, there is no volumetric change or change of pressure in the circulation circuit but a change in the relative amount and distribution of gas and oil. Gas is removed from the circuit and an equal quantity of oil is introduced without disturbing the pressure in the circulation circuit.

While there is a removal of a quantity of gas at the bottom of the circuit and at the pressure existing there, for an equal quantity of oil, a large portion of the gas, measured at atmospheric pressure, is recovered and returned to the circulation circuit higher up and at a lower pressure through the valves 68, as previously described. Only that remaining in the displacement chamber after the pressure has been lowered to that in the ascending column of mixture at the uppermost valve 68, is discharged into the well, and must expand to atmospheric pressure, from which it has to be re-compressed by compressor 65 and returned to the circuit at the pressure of the inlet of compressor 24.

The system appears to be quite intricate; but a graphical and mathematical analysis of its operating characteristics shows that, while its various circulation circuits are intermeshed and inter-related so that a change in one circuit affects all of the others, it is nevertheless largely self-regulatory and simple of adjustment and in

operation. When the pressures and flows of gas and oil are adjusted at mixer 28, the various portions of the circulation system below ground, due to the inter-relationship and inter-meshing, adjust themselves to the values corresponding to the adjustment of pressures and flows and the timing of the gear of the displacement chamber.

Attention is called to the fact that, in addition to supplying high pressure gas for the operation 10 of the displacement chamber and carrying out the virgin oil after its injection into the circuit, the circulation system described decreases the hydrostatic pressure to be handled throughout the system in proportion to the ratio of the 15 amount of gas and oil in the ascending column of fluid. If there is 35% of gas, the hydrostatic pressure in the separator chamber is only a little over 65% of the pressure corresponding to a column of solid oil from that point to the surface 20 of the ground. The gas in the circulation circuit which is recompressed by compressor 24 is never at a pressure less than the pressure in 25, which is of the order of from 100 to 300 pounds per square inch. There is a large saving of energy required for recompression because of the well known fact that it takes far less energy to compress, for example, from 200 pounds to 400 pounds per square inch than it does to compress from atmospheric pressure to 200 pounds. Likewise 30 there is a saving due to the fact that there is a smaller slippage between gas and liquid at pressures ranging from 200 pounds per square inch upward than between atmospheric pressure and 200 pounds per square inch, with a consequent 35 advantage in the lifting effect due to the gas in the ascending column of mixture. The recovery of a considerable portion of the gas from the displacement chamber and its injection into the ascending column of mixture where it assists in lightening the pressures and in lifting the liquid, produces a substantial saving of energy. The combined effect of these savings and advantages makes it possible to bring to the ground surface a barrel of liquid with a much 45 smaller number of cubic feet of free gas and a much smaller expenditure of energy for compressing the gas and circulating the mixture than is possible with other methods of gas-lift or displacement gas-lift.

In addition to these advantages resulting from the use of the liquid and gas circulation, hydro-pneumatic compression, and centrifugal separation, it is pointed out that a large number of wells, each requiring different pressures at the 55 displacement chamber due to different depths of pumping and different production, may be served by one central compressor plant operating at a fixed pressure. The hydropneumatic compression stage in each well makes the necessary adjustment of pressures without loss of energy and makes it possible to deliver gas at, for example, 60 2000 pounds per square inch pressure at the displacement chamber with not over 700 pounds per square inch at the compressor above ground.

Other displacement gas-lift methods require 65 either the high pressure to be delivered by a mechanical compressor or a very large volume of gas with a slug-flow method. In either case, the quantity of free air and total energy required 70 exceed the amounts required by this method.

Attention is called to the fact that, with this system, the high pressure gas employed in the lifting operation is entirely isolated from the well and oil-bearing structures at all times.

When the displacement chamber discharges its

gas into the well, it is in relatively small volume, and it passes upward between the well casing and the outer tubing to the outlet 29 where it goes to the suction of the compressor, the pressure being maintained at atmospheric pressure, or lower if desired. Thus no back pressure is applied to the oil structure, thus fulfilling one of the important objects of the invention.

Attention is called to the fact that, since the displacement chamber and its oil inlet valve may 10 be placed very near the bottom of the well if needed, since the operation of the system does not depend upon any condition in the well external to the mechanism, such as gas pressure or deep submersion, excepting submersion sufficient 15 to cause the oil in the well to open the foot-valve 41 and flow in and fill the displacement chamber, and that since the operation of the displacement chamber is positive and can be made to operate at any depth, it is possible with 20 this system to pump oil from the bottom of wells of any depth, thus fulfilling one of the important objects of the invention.

Attention is called to the fact that, since the 25 operation of the system is started without any rocking or pulsation of the fluid in the well, and since, in operation, the amount of the intermittent withdrawal of oil from the well is limited to the capacity of the displacement chamber, this 30 system does not produce any detrimental surges or sudden changes of pressure that might be destructive to the casing or oil structure around the hole, thus fulfilling one of the important objects of the invention.

Attention is called to the fact that, since the 35 required submersion of the displacement chamber is small and usually less than the penetration of the well bore below the top of the oil-bearing formation, it is possible to pump oil from the well after the virgin gas has been depleted 40 so that the oil does not rise above the level of its entry into the well, thus fulfilling another of the objects of the invention.

It is pointed out that, with this method, all 45 of its operations are within closed circuits from which losses of liquid and gas are very small, if present at all. There are but two external outlets above ground, outlet 44, from which the output of oil is withdrawn, and outlet 27 into which gas to supply losses may be introduced or 50 where gas may be discharged in those cases where the well itself makes more gas than needed in the system. In wells that have considerable gas pressure which forces the oil level above the oil-bearing formation, the apparatus is installed no 55 deeper than necessary to maintain the required submersion of the displacement chamber at all times. When the oil level has lowered below the range of the apparatus as installed, it is lowered by lengthening the tubing lines and adjusting 60 the pressures to suit the changed conditions. Thus it will be seen that any work done by any gas pressure within the oil-bearing structure tending to lift the oil, is utilized when present; but it is not essential to the operation of the 65 method of pumping. Furthermore, all gas coming from the well is saved. In most cases, the gas compressor is located in a central plant supplying a group of wells; and the gas coming from the wells is passed through a plant which removes 70 any gasoline carried by it, after which, it enters the circulation again to acquire more gasoline. The intimate mixture of the gas and oil, the repeated hydraulic compression and decompression of the gas, and the long travel in inti- 75

mate mixture in making several circuits of the system before going to the plant which removes the gasoline, will produce maximum absorption of gasoline. Thus it will appear that this method 5 meets the object of the invention as to operation under conditions of economy and with a minimum of wastage of oil and gas.

The combination of parts and the method of operation hereinbefore described are to be used 10 in wells in which the virgin gas has been depleted and the fluid level lowered to such a point that the hydrostatic pressure of a column of oil of a height equal to the distance from the fluid level to the ground surface is greater than the 15 maximum delivery pressure of compressor 24 above atmospheric pressure; and this combination and the stated method may be used when the stated hydrostatic pressure is of any value up to several times the maximum delivery pressure 20 of compressor 24. Before the fluid level has lowered to a stage of this order, the same equipment may be used and a modified mode of operation employed to pump the oil from the well, in which the outlet 35 from the separator 33 is plugged, the 25 oil-pump is disconnected and nothing but gas is forced downward in the space between the tubings 1 and 2. Except for the elimination of the oil circulation and, consequently, the separating action of the separator 33, the mode of operation 30 is the same as hereinbefore described.

The system is very flexible and capable of modification to suit the large range of conditions to be encountered in the oil fields, both as 35 to the condition and history of the wells and as to the equipment in use prior to the installation of the new system and to be associated with it. The system may be operated with all of its component parts in use or with some of those described eliminated and the combinations altered 40 to suit special conditions, as, for instance, operating without using a gas-discharge-line and using a reciprocating movement of one of the other strings of tubing for the operation of the valves, or using an entirely different method of 45 operating the valves either with or without using a gas-discharge-line.

In the specific embodiment of the invention used as an illustrative example, a displacement chamber is used as a means of drawing liquid 50 from the well and discharging it into the conduit through which it is lifted to the ground level. No specific form of chamber is necessary nor is a displacement chamber an essential detail of the invention. Any equivalent displacement means 55 will function in combination with the other elements. The essential requirement for the displacement means included as an element of the invention is that it draw liquid from the well into a receptacle, represented by the displacement 60 chamber in the illustrative example, and that the liquid be positively displaced and forced out of the said receptacle by a means actuated either wholly or partly by gas pressure, the displacement of the liquid being accomplished either directly by 65 the gas itself or through an intermediary means or equivalent, and the gas thus used by the displacement means being, also, employed, either before or after use in the displacement means, or both before and after, in aerating or lightening 70 the columns of liquid in the conduit system, either descending or ascending, or both descending and ascending, as a means of reducing the pressures in the system and assisting in bringing the liquid to the ground level.

75 Attention is called to the fact that, with this

method, the long lines of the tubing are not subjected to large alternations of stress, as is the case with "sucker-rod pumps" where the weight of the entire column of fluid filling the oil-tubing is transferred from the rod to the tubing and back 5 to the rod again at each stroke; hence there is no appreciable wear of the tubing and well casing due to the elongation and return due to the alternating changes in stress which, in the case of the "sucker-rod pumps", increase from nothing at the top progressively with depth to a maximum of several inches at the bottom. With our system, the movement of the inner tubing, or gas-discharge-line, is slight and of low periodicity; and the variation of stress is very slight. 15

While we have shown and described specific embodiments of the invention, we do not limit ourselves to the exact details of construction disclosed but may employ such changes in construction and arrangement of parts, and such modifications and equivalents as come within the scope of the appended claims. 20

We claim:

1. In apparatus for pumping wells, strings of tubing, installed in a well; connecting means 25 adapted to provide, in combination with the said strings of tubing, conduits for the conveyance of a descending flow of fluid from the upper end of the strings of tubing to the lower end of the same and an ascending flow of fluid from the lower end 30 to the upper end of the said strings of tubing; a gas-discharge-line, comprising a string of tubing extending from a point near the lower ends of the strings of tubing first above named and extending upward toward the ground level; 35 means for supporting the gas-discharge-line and actuating and timing a reciprocating movement of the same; valves providing communication between the gas-discharge-line and one of the conduits aforesaid in a manner to permit flow 40 of fluid from the gas-discharge-line into the conduit but not in the reverse direction; a displacement chamber near the lower ends of the strings of tubing and the gas-discharge-line; means for supplying gas to the displacement chamber; 45 valves adapted to be actuated by the stated reciprocation of the gas-discharge-line and to permit flow between the said means for supplying gas and the displacement chamber, between the displacement chamber and the gas- 50 discharge-line, and between the displacement chamber and the space without the apparatus in the well in sequence; valves permitting flow of fluid in one direction only from the space in the well external to the apparatus in the well into 55 the displacement chamber and between the latter and the conduit conveying the ascending flow of fluid first above described; means for maintaining a circulation of fluid through the conduits for the conveyance of the descending and ascending flows of fluid first above described; and means for maintaining the required amounts of fluid in the conduits and discharging any increase of fluid therefrom. 60

2. In apparatus for pumping wells, strings of tubing in concentric assembly, installed in a well; connecting means adapted to provide, in combination with the said strings of tubing, conduits for conveying a flow of fluid downward in one conduit from the upper end of the strings of tubing to the lower end of the same and in the reverse direction in another conduit; a gas-discharge-line, situated concentrically within the inner of the strings of tubing above named and comprising a string of tubing sections, supporting 65 70 75

rod sections, and valves at intervals between the tubing sections, the gas-discharge-line being connected to the conduits aforesaid near their lower ends and extending upward from the same and 5 being adapted to have a reciprocating movement, the said valves being adapted to allow flow of fluid from the gas-discharge-line into one of the conduits surrounding it but not in the reverse direction; means for supporting the gas-dis- 10 charge-line at the ground level and of actuating and timing a reciprocating movement of the same; a displacement chamber near the lower end of the strings of tubing and means for supplying gas to the displacement chamber; valves 15 adapted to be actuated by the stated reciprocating movement of the gas-discharge-line and to control the filling of the displacement chamber with gas and the emptying of the same; valves allowing flow of fluid in one direction only between the 20 space in the well external to the apparatus in the well and between the displacement chamber and the conduit which conveys the fluid upward to the ground level as first above described; and means for maintaining flow of fluid through the conduits 25 and of discharging increase of fluid above ground.

3. In apparatus for pumping wells, two strings of tubing in concentric assembly, installed in a well; a housing providing a structural connection between the two strings of tubing at their 30 lower ends and passageways providing, in combination with the strings of tubing, conduits for conveying a flow of fluid downward in one conduit and upward in another between the said housing and the upper ends of the strings of tubing; a gas-discharge-line concentrically within one of the strings of tubing and comprising a 35 string of tube sections extending from a connection with the said housing upward toward the upper end of the strings of tubing aforesaid and 40 adapted to have a limited reciprocatory movement axially with reference to the housing; valve means for allowing flow of fluid from the gas-discharge-line into one of the conduits but not in the reverse direction; an extension of the gas- 45 discharge-line into and a valve actuating mechanism within the housing; means for supporting the gas-discharge-line at the upper end thereof and of actuating and timing the reciprocatory movement aforesaid; a displacement chamber 50 within the housing; means for supplying gas to the displacement chamber; valve means adapted to be actuated by the valve actuating mechanism aforesaid and the reciprocatory movement of the gas-discharge-line and to control the filling of the displacement chamber with 55 gas and the emptying of the same in alternation; means for admitting liquid from the well into the displacement chamber and from the said chamber into the conduits aforesaid, the said 60 means including valves for preventing flow in the reverse direction; and means for maintaining flow of fluid through the conduits and for discharging excess of fluid above ground.

4. In apparatus for pumping wells, an assembly of strings of tubing, installed in a well; means of communication between the lower ends of the strings of tubing forming, in combination therewith, conduits for conveying a flow of fluid downward from the upper end to the lower end and 65 back to the upper end of the assembly; a gas-discharge-line, comprising a conduit extending from the lower end of the assembly upward toward the upper end of the same; a displacement means near the lower end of the assembly; 70 means for supplying gas under pressure for the

functioning of the displacement means; valves adapted to admit gas from the said means for supplying gas into the displacement means, for discharging gas from the displacement means into the gas-discharge-line, for admitting liquid 5 from the well into the displacement means, and for discharging liquid from the displacement means into one of the conduits above named; valve means for discharging gas from the gas-discharge-line; means for actuating and timing 10 the valves aforesaid in a manner to cause the displacement means and the valves to co-act to cause the displacement means to draw liquid from the well and to discharge the same into one of the conduits first above named; means for maintaining flow of fluid into the upper end of one of the conduits first above mentioned and outward from the other of the said conduits; and means for discharging increase of fluid at the upper end of the assembly of strings of tubing. 20

5. In apparatus for pumping wells, strings of tubing installed in a well and forming two conduits for the conveyance of fluid between the upper and the lower ends of the strings of tubing; a displacement means at the lower end of the 25 two conduits and a gas-discharge-line extending from the displacement means upward toward the upper end of the conduits; valve means for permitting flow of fluid from the gas-discharge-line into one of the two conduits but not in the reverse direction; means for supplying gas under pressure to the displacement means; valve means adapted to admit gas from the means of supplying gas to the displacement means, to discharge gas from the displacement means into the 30 gas-discharge-line, to exhaust gas from the displacement means, to admit liquid from the well into the displacement means, and to discharge liquid from the displacement means into one of the two conduits first above named, the said 35 valve means being adapted to be actuated and timed in the sequence required to cause the displacement means and the said valves to co-act to draw liquid from the well and discharge liquid into one of the two conduits aforesaid; and 40 means for discharging increase of fluid at the upper end of the conduits. 45

6. In apparatus for pumping wells, strings of tubing, installed in a well; connecting means adapted to provide, in combination with the said 50 strings of tubing, conduits for the conveyance of a descending flow of fluid from the upper end of the strings of tubing to the lower ends of the same and an ascending flow of fluid from the lower end to the upper end; a displacement means near the lower end of the strings of tubing; means for supplying gas under pressure for the functioning of the displacement means as described; a gas-discharge-line, comprising a 55 string of tubing extending from a connection with the displacement means upward toward the ground surface; valve means adapted to admit gas to the displacement means, to discharge gas into the gas-discharge-line, to admit liquid from the well into the displacement means, and to discharge liquid from the displacement means into the aforesaid conduit conveying the ascending flow of fluid; valve means for discharging gas from the gas-discharge-line into one of the 60 conduits aforesaid at a point above the displacement means having a pressure within the conduit very much less than the pressure in the displacement means, the valve means being adapted 65 to prevent flow in the reverse direction; means 70

75

for actuating and timing the said valve means in a manner to cause the displacement means and the valve means to co-act to cause the displacement means and the valve means to draw liquid 5 from the well and to discharge the same into the aforesaid conduit conveying the ascending flow of fluid; and means for maintaining a flow of fluid downward to the lower end of the strings of tubing through one of the conduits and back 10 to the upper end in another conduit and discharging increase of fluid at the ground level.

7. In apparatus for pumping wells, strings of tubing, in concentric assembly, installed in a well; means for communicating between the strings of 15 tubing at their lower ends, forming means for conveying fluid downward through a passageway from the upper end to the lower end of the assembly and a flow of fluid in the upward direction in another passageway; displacement means 20 connected to the strings of tubing at the lower end of the assembly; means for supplying and conveying gas under pressure to the displacement means; valve means for admitting gas to the displacement means and for exhausting gas from 25 the same in sequence as required for the alternate filling and emptying of the displacement means, the gas thus used being exhausted into the aforesaid passageway for conveying fluid in the upward direction at a point far enough above the 30 displacement means and the lower end of the assembly of tubing for the pressure in the passageway last named to be sufficiently lower than the pressure in the displacement means to provide a substantial operating power head for the displacement means; valve means for admitting liquid from the well into the displacement means and for discharging fluid from the displacement means into the aforesaid passageway conveying fluid in an upward direction, the valve means being adapted to prevent flow in the reverse direction; means for maintaining and regulating the flow of fluid into the upper end of the aforesaid passageway conveying fluid in the downward direction; and means for discharging and regulating the flow of fluid out of the passageway carrying the upward flow of fluid and withdrawing increase of fluid.

8. In apparatus for pumping wells, strings of tubing, assembled in a well; means of communication between the strings of tubing at the upper and lower ends thereof and forming in combination therewith, means for conveying a flow of fluid downward from the upper end of the assembly to the lower end of the same in one conduit 55 and a flow of fluid upward from the lower end to the upper end in another conduit; a displacement means at the lower end of the assembly; a

means for supplying gas under pressure to the displacement means through one of the conduits aforesaid; means for exhausting gas from the displacement means upward to a point at a distance above the displacement means including means 5 for discharging gas into one of the conduits aforesaid, the pressure at the point of discharge being very much lower than the pressure at the lower end of the conduit last named at any time, the valve means being adapted to prevent flow in the 10 reverse direction; valve means adapted to admit gas from the means for supplying gas to the displacement means, to discharge gas from the displacement means into the means for exhausting gas aforesaid, to admit fluid from the well into 15 the displacement means, and to discharge fluid from the displacement means into the aforesaid conduit for conveying an upward flow of fluid, the said valve means being adapted to be actuated and timed to operate in the sequence necessary to cause the displacement means and the said valve means to coact to draw fluid from the well and discharge the same into the aforesaid conduit for conveying an upward flow of fluid; and means for maintaining and regulating the 20 flow of fluid in the conduits aforesaid at their upper ends and discharging increase of fluid.

9. In apparatus for pumping wells, strings of tubing installed in a well; means of communication between the strings of tubing forming therewith conduits for conveying fluid downward through one conduit to the lower end of the strings of tubing and for conveying fluid upward through another conduit from the lower end to the point of beginning; a displacement means 30 connected to the strings of tubing at the lower end; means for supplying gas under pressure to the displacement means; means for admitting gas to the displacement means and for exhausting gas from the same, the means of exhausting 35 gas including means for conveying the exhaust gas to a point at a distance above the displacement means and injecting the gas into the aforesaid conduit conveying an upward flow of fluid at a point at such a distance above that the pressure in the said conduit is very much less than the pressure at the lower end of the same conduit; valve means for admitting fluid from the well into the displacement means and for discharging fluid from the displacement means into 40 one of the conduits aforesaid; the valve means being adapted to prevent flow in the reverse direction; means for actuating the valve means; and means for discharging fluid at the upper end of the strings of tubing.
